STUDIO LIGHTING SYSTEM

Gilbert H. Tunney, Hellam, Pa.

Application April 9, 1956, Serial No. 576,866

3 Claims. (Cl. 240—3)

The present invention relates generally to lighting systems, and is particularly directed to lighting systems for the production of entertainment programs as in television studios and the like.

The particular embodiment of the present invention, which is illustrated in the drawings and which will be described hereinafter in greater detail, comprises generally at least one fixed overhead track, and a second track mounted on the first-named track for rotative movement, and movement longitudinally and transversely of the first-named track. The second track is adapted to carry lighting equipment so as to move the same along any desired path to a selected location.

Heretofore, as is well known to those versed in the art, television studios and other places having similar lighting requirements were conventionally constructed with fixed overhead pipes, to which were clamped pieces of lighting equipment. The ceiling or a plurality of suitable fixtures were provided with a multitude of electrical outlets to accommodate various arrangements of the lighting equipment. Each lighting device was normally provided with a screw clamp to permit securement to the pipes at the desired location. Hence, to obtain a high degree of flexibility in use, it was necessary to employ a great number of lighting devices which are themselves relatively expensive and require the use of expensive operating equipment. Further, prior studio lighting systems have served to limit the versatility of program production in any one studio. For example, the theater type studio, having a high ceiling, required a lighting system which was not adaptable to the repetitive type of program studio.

Accordingly, it is an object of the present invention to provide a studio lighting system having an extremely high degree of flexibility in use, and which completely fulfills the lighting requirements for a wide variety of studios. For example, the device of the present invention serves to provide base lighting as well as accent lighting, and is equally well adaptable for use in studios having relatively high or low ceilings.

It is another object of the present invention to provide a studio lighting system of the type described which serves to substantially reduce the necessary number of lighting devices, and in which the pieces of lighting equipment may be quickly and easily moved along any desired path to any selected position. By the present invention, it is possible to relocate lighting equipment without the laborious and time-consuming clamping and unclamping operations, which were heretofore necessary.

It is a further object of the present invention to provide a studio lighting system having the characteristics mentioned in the foregoing paragraphs which is simple in construction and durable in operation, which is effective for its intended objects, and which can be produced and operated at a reasonable cost.

Other objects of the present invention will become apparent upon reading the following specification and re-

2

ferring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

Figure 1 is a top plan view showing a television studio 10 employing the lighting system of the present invention.

Fig. 2 is a perspective view showing a lighting system constructed in accordance with the present invention.

Fig. 3 is a fragmentary elevational view showing a novel feature of construction of the present invention.

Fig. 4 is an elevational view of the construction shown in Fig. 3 and taken at right angles with respect thereto.

Fig. 5 is a perspective view of a second embodiment.

Fig. 7 is a section partially in elevation on the line 7—7 of Fig. 5.

Fig. 8 is a section partially in elevation on the line 8—8 of Fig. 7.

Fig. 9 is a section partially in elevation on the line 9—9 of Fig. 8.

Fig. 10 is a detail perspective view of the locking frictional brake of an upper main-rail trolley.

Fig. 11 is a section partially in elevation on the line 11—11 of Fig. 5.

Fig. 12 is a section on the line 12—12 of Fig. 11.

Fig. 13 is a section similar to Fig. 11, showing a modification of the motor-driven means.

Fig. 14 is a section on the line 14—14 of Fig. 13.

First embodiment, Figs. 1—4

Referring now more particularly to the drawings, and specifically to Fig. 1 thereof, the embodiment of the invention illustrated therein comprises a television studio, generally designated 10A having, for example, a kitchen set 11A situated in one corner of the room, a play setting 12 situated in another corner of the room, a news-caster's desk 13A at one end of the room, and a panel program set 14 in still another corner of the studio.

A plurality of parallel spaced overhead I beams, or other suitable tracks, extend longitudinally of the studio 10A and are designated 15A, 16A, 17A, 18A, 19A and 20A. The longitudinally extending tracks are fixedly secured to the ceiling (not shown) by any suitable means. It will be observed that the longitudinal tracks are spaced inwardly from the studio sides and terminate short of the studio ends. While the parallel spaced tracks 15A—20A have been described and illustrated as extending longitudinally of the studio 10A, as preferred, it will be appreciated that such tracks may also be arranged transversely of the studio, which may be advantageous under certain circumstances.

A plurality of transversely disposed tracks 25, 26, 27, 28, 29, 30 and 31 are each arranged below an adjacent pair of the longitudinally extending tracks 15A—20A and movably supported by the latter. That is, each of the transverse tracks 25—31 is suspended from the adjacent pair of longitudinally extending tracks and mounted for rotative movement, as well as movement longitudinally and transversely with respect to the longitudinal tracks 15A—20A. Suspended from each of the transverse tracks 25—31 are a plurality of pieces of lighting equipment 32, 33, 34, 35, 36, 37, 38 and 39, each of which are preferably movable along the associated transverse track.

Additional transverse tracks 40 and 41 are each arranged below the longitudinal tracks 17A and 19A, respectively. The transverse tracks 40 and 41 are also

mounted for rotative movement, as well as movement longitudinally and transversely with respect to the tracks 17A and 19A, respectively. Pieces of lighting equipment 42 and 43 are suspended below the transverse tracks 40 and 41, and are preferably movable therealong.

Extending peripherally around the inside of the studio 10A is a substantially rectangular, overhead I beam or track 45, which is fixedly positioned as by securement to the studio ceiling or walls by any suitable means (not shown). Arranged below and movable along the peripheral track 45 are a plurality of pieces of lighting equipment 46, which are preferably pivotally carried by trolleys (not shown) rolling along the peripheral track.

In Fig. 2, the construction is seen in greater detail, the longitudinal I beams or tracks 15A and 16A extending, preferably horizontally, overhead and being fixedly secured to the studio ceiling (not shown) by hangers 50 and 51. Electrical outlets 52B and 53 may be spaced along the I beam tracks 15 and 16, or may be provided in the ceiling or other suitable location, as desired. Each said longitudinal track 15A—20A has a vertical web 53A.

A pair of depending movable elements or trolleys 54 and 55 are movable along the lower flanges of the I beams 15A and 16A, respectively. Pivotally connected to and depending, respectively, from the trolleys 54 and 55 are a second pair of movable elements or trolleys 56 and 57'. Thus, the trolleys 56 and 57' are movable with the trolleys 54 and 55 longitudinally along the I beams 15A and 16A, and are rotatable with respect to the latter trolleys.

The I beam 25 is arranged transversely of and below the I beams 15A and 16A and extends between the trolleys 56 and 57', having its upper flange supported by the latter trolleys. It will be observed that the I beam 25 has its opposite ends extending beyond the trolleys 56 and 57' and provided with lugs or bosses 58, for reasons to become apparent presently. It will now be appreciated that the transverse track 25 is movable with the trolleys 56 and 57' longitudinally along the tracks 15A and 16A, and further, that the transverse track 25 is movable relative to the trolleys 56 and 57' transversely of the tracks 15A and 16A, the latter movement being limited by engagement of the lugs 58 with the trolleys 56 and 57'. In addition, the transverse track 25 is rotatable about vertical axes upon movement of the trolleys 54 and 55 along the tracks 15A and 16A, and simultaneous movement of the track 25 relative to the trolleys 56 and 57'. It will be noted that this rotative movement of the track 25 is permitted by the pivotal connection between the adjacent pairs of trolleys, which will be described hereinafter in greater detail.

The fluorescent bank or other lighting device 33 is carried by the lower end of a pantograph 60, which has its upper end pivotally secured to an underslung trolley 61 riding on the lower flange of the transverse track 25. Thus, the lighting device 33 is movable along the transverse track 25 with the trolley 61, and of course, is movable with the transverse track. In addition, the lighting device 33 is rotatable about the swivel 62 and movable vertically with the pantograph 60. Such pantographs are normally flexible to permit lateral or sidewise displacement as required. A wire 63 may be connected between the lighting device 33 and the outlet 52B to provide electric power for the lighting device.

A spotlight is illustrated at 32, being mounted for rotative movement about a horizontal axis in the yoke 65. The yoke is fixedly secured by a rod 66 to an underslung trolley 67 which rides along the lower flange of the transverse track 25. Thus, the spotlight 32 is movable with the transverse track 25 and movable relative thereto with the trolley 67. A cord 68 provides electrical connection with the outlet 53, the cords 63 and 68 being of sufficient length to permit substantial movement of the fluorescent bank and spotlight 32.

In Figs. 3 and 4 are shown more detailed views of the

trolleys 55, 57' and 67. The trolley 55 includes a carriage 70 having a plate 71 below the lower flange of the longitudinal track 16A. The plate 71 is substantially rectangular in configuration and is formed adjacent to its corners with four upstanding legs 72. The upper end portion of each leg 72 is bent downwardly, as at 73, into parallel, outwardly spaced relation with respect to the adjacent leg portion. A roller 74 is disposed inwardly of and journaled in each of the legs 72, the rollers being journaled in the parallel leg portions to provide sufficient bearing surface. It will now be understood that the rollers 74 ride upon the lower flange of the I beam 16A and thus movably support the underslung carriage 70 of the trolley 55.

The trolley 57' is substantially identical in construction with the trolley 55, but inverted in disposition, and includes a carriage 80 comprising a substantially rectangular plate 81 which is arranged below the plate 71 of the trolley 55. The plate 81 is provided at its corners with four depending legs 82 which have their lower end portions 83 bent upwardly into parallel, outwardly spaced relation with respect to the adjacent leg portions. Disposed inwardly of the legs 82 are rollers 84, each being journaled in the parallel spaced portions of one of the legs 82. A pivot pin or bolt 85 extends through washer 86, carriage plate 71, spacer 87, carriage plate 81, and washer 88, the bolt being locked in loose condition to permit relative rotation between the carriage plates 71 and 81. Thus, the carriage 80 depends from and is swivelly connected to the carriage 70. It will be understood that the transverse I beam or track 25 may have its upper flange movably supported on the rollers 84 of the trolley 57'.

The underslung trolley 67 includes a plate 90 disposed below the lower flange of the transverse track 25 and having a pair of upstanding legs 91. The legs 91 have their end portions 92 bent downwardly into parallel, outwardly spaced relation with respect to the adjacent leg portion and serve to journal the rollers 93 which ride upon the lower flange of the I beam 25. An internally threaded socket 94 has its closed end fixedly secured, as by welding or other suitable means, to the plate 90 and is adapted to receive the upper end of the rod 66 for supporting the spotlight 32. It will now be understood that the trolley 67 supports the spotlight 32 for movement with the transverse track 25 as well as movement relative to the latter. While the trolley 67 has been illustrated and described as having two rollers 93, and the trolleys 55 and 57' have been illustrated and described as having four rollers 74 and 84, it will be appreciated that the number of rollers employed on the particular trolleys may be varied according to the load, frequency and duration of operation, and other factors.

Referring now again to Fig. 1, it will be understood that the transverse I beams or tracks 26—31 are all mounted in the same manner as described above in connection with the transverse track 25. Hence, each of the transverse tracks 25—31 is mounted for rotative movement, and movement longitudinally and transversely with respect to the associated longitudinal tracks. Further, the individual lighting devices carried by the transverse tracks are movable with the latter, and may be movable relative thereto in both translation and rotation.

The transverse tracks 40 and 41 may be suspended from the longitudinal tracks 17A and 19A by a single pair of swivelly connected trolleys, to thereby permit of rotative movement of the transverse tracks 40 and 41 as well as longitudinal and transverse movement with respect to the associated longitudinal tracks. The lighting elements 42 and 43 may also be supported by underslung trolleys from the transverse tracks 40 and 41 for movement with the latter as well as movement relative thereto.

Similarly, the lighting devices 46 may be suspended from the track 45 by an underslung trolley and thereby

mounted for movement along the track 45 as well as for rotative movement.

While the longitudinal, transverse and peripheral tracks have been illustrated and described as horizontally disposed, it will be understood that such construction may be varied to suit the requirements of a particular studio. Further, while the transverse tracks have been shown as freely movable, it is appreciated that motive power and braking force may be employed within the scope of the present invention.

From the foregoing, it is seen that the present invention provides a studio lighting system which fully accomplishes its intended objects, and which is well adapted to meet practical conditions of use.

Second embodiment

In this practical embodiment, I provide three main overhead and straight supporting rails, which are horizontal, and parallel to each other, and 15 feet above the floor of the room. The invention is not limited to horizontal or parallel rails. Many other details are described in this disclosure, without limitation thereto. These main rails are designated as longitudinal rails, because they are parallel to the length of the room. The length of these main rails is 55 feet.

I provide three main-rail trolleys on each main rail.

In this embodiment, I provide three fixture-rails on trolleys, which are horizontal and straight, and are located 14 feet above the floor of the room. These fixture-rails are also designated as lateral rails. They may be held parallel to the end walls of the room, or inclined thereto about a vertical axis.

Each main-rail trolley is connected by a swivel, which has a vertical axis, to a lower fixture-rail trolley.

Each fixture-rail is supported in a set of fixture-rail trolleys.

Each fixture-rail has a junction-box fixed thereto, an associated main cable, and an associated cable-supporting rail. In this example, the cable-supporting rails are straight, horizontal, located seventeen feet above the floor of the room, and each cable-supporting rail has six or eight cable-supporting trolleys mounted thereon, for supporting the main length of a respective main cable. Each main cable has an inlet branch which extends upwardly from the fixed electrical power inlet of the junction box, and an outlet depending branch to the respective junction box. The main cables are thus effectively held at a safe level above the working space of the floor.

Branch cables lead from each junction box to lamps which are connected to fixture-trolleys which are movable on the respective fixture-rail. These branch cables are also prevented from dangling below a safe level.

Instead of manually shifting the fixture-rails longitudinally along the main rails, I may provide the main-rail trolleys which are associated with each fixture-rail, with motors 270 for actuating said main rail-trolleys. In such case, I provide the respective junction box with a motor circuit which is wholly independent of its lighting circuit, and I provide each motor circuit with a control switch at a remote control station at one end of the room or at other convenient location. The electric motors 270 may be of the familiar reversible type, in which case, the switch is a reversing switch.

If the fixture-rails are manually shifted, I provide each main-rail trolley with a locking brake which is normally set to locking position, so that it must be manually released before shifting the main-rail trolley along its main rail.

If the fixture-rails are shifted by electric motors along the main rails, I provide each main-rail trolley with a retarding brake which slips under moderate force.

The trolleys which support the fixture rails and the fixtures are provided with said retarding brakes.

For convenience of illustration, Fig. 5 shows two hori-

zontal main rails 10, which are parallel to each other, and which are held fixed by straps 11 to a ceiling or other overhead support, which is not shown. There may be any number of horizontal and parallel main rails 10, 5 which are also designated as longitudinal rails. Fig. 5 shows three horizontal, lateral or fixture-supporting rails 10a, of which there may be any number. Each horizontal fixture-supporting rail 10a is associated with a horizontal cable-supporting rail 50. These horizontal 10 cable-supporting rails 50 are held fixed and parallel to the main rails 10, by respective straps 51 which are fixed to the ceiling or other overhead support. For convenience of illustration, the three cable-supporting rails 50 are shown at one side of their two associated main 15 rails 10 which are illustrated in Fig. 5. These cable-supporting rails 50 may be located above and centrally intermediate their two associated main rails 10.

All the rails 10, 10a and 50 are I-shaped and identical in this embodiment. Each said rail or track 10 has a 20 horizontal top flange 14, a vertical web 13, and a bottom horizontal flange 15. Each said rail or track 50 has a bottom horizontal flange 53. Each said rail or track 10a has a top horizontal flange 18, a vertical flange 18f, and a bottom horizontal flange 15f.

25 Each main rail 10 is associated with a suitable number of upper or main-rail trolleys 16, at least two such trolleys 16 being provided for each fixture-supporting rail 10a.

Each main-rail trolley 16 is associated with a fixture- 30 rail trolley 17. In this embodiment, each fixture-rail 17 is below its main-rail 16.

Each fixture-rail 10a is associated with fixture-supporting trolleys 17a. Each cable-supporting rail 50 is 35 associated with cable-supporting trolleys 52.

These trolleys 16, 17, 17a, 52 have respective U-shaped frames. Each said trolley-frame has a horizontal flange 20 and two vertical and parallel flanges 19. Each said trolley 16, 17, 17a, 52 has four wheels 21, 40 which are turnably connected to respective flanges 19 by pins 22. There are two wheels 21 at each side of the respective flange 12. The wheels 21 of main-rail trolleys 16 roll upon the bottom flanges of main rails 10. The top flanges 18 of fixture-supporting rails 10a are supported on the wheels 21 of the fixture-trolleys 17. The wheels 45 21 of the cable-supporting trolleys 52 roll on the horizontal flanges 53 of the cable-supporting rails 50. Each wheel 21 has an enlarged annular rim 21a, which turnably abuts the respective side edge of the respective rail-flange.

50 There may be a limited vertical movement or limited tilting movement between each rail 10, 10a, 50 and its associated trolleys 16, 17, 52, and between each rail 10 and its associated trolleys 17a.

Thus, as shown in Figs. 6 and 8, each main-rail trolley 55 16 may be provided with parallel shafts 23a and 23, which are perpendicular to the respective pair of flanges 19, and which are turnably mounted in said flanges 19. Said shafts 23a and 23 have respective rolls 24a and 24 fixed thereto. Each said roll 24a and 24 is located mid- 60 way between the respective flanges 19. As shown in Fig. 8, when the four wheels 21 of main-rail trolley 16 are in normal position, in which they abut the top face of flange 15, said rolls 24a and 24 are located below and equally vertically spaced from said flange 15. The main-rail trolley 16 can be tilted at either end thereof relative to the associated flange 15, until the roll 24a or roll 24 abuts the bottom face of said flange 15. The annular rims 21a always abut or are very close to the side edges of flange 15. Hence, if the top face of flange 15 is not perfectly planar and horizontal, the limited relative tilting movement of main-rail trolley 16 permits its wheels 21 to ride over any irregular part of the top face of flange 15. This illustration applies to the other trolleys 17, 17a, 52. The rims 21a prevent relative side

movement between the trolleys and their rails, and always keep the trolleys aligned with their rails.

The shafts 23a and 23 may be stud-shafts which are non-turnably fixed to their respective flanges 19; in which case the rolls 24a and 24 are turnable relative to the non-turnable stud-shafts 23a and 23.

Also, the pins 22 of wheels 21 may be turnable or non-turnable. If non-turnable, the wheels 21 are turnable on their pins 22.

Each lower fixture-rail trolley 17 in this embodiment is turnable around a vertical axis, relative to its upper associated main-rail trolley 16.

The frame of each fixture-rail trolley 17 has an inverted U-shape, so that the horizontal flanges 20 of the frames of associated main-rail and fixture-rail trolleys 16 and 17 are adjacent each other.

A vertical shaft 140 has a head 143 which abuts a spacing anti-friction washer 142, which abuts the next-adjacent flange 20. Said shaft 140 has a shank whose bottom end has an external thread. Said shank of shaft 140 extends through bores of anti-friction washer 142, upper flange 20, a spacing and anti-friction washer 142, the lower flange 20, an anti-friction spacing washer 142, and an assembly nut 144 which engages the thread at the bottom end of said shank. Each lower trolley 17 can turn freely around the axis of shaft 140, in this embodiment.

If the main-rail trolleys 16 are manually shifted along the main rails 10, in order to shift a fixture-rail 10a bodily along its main rails 10, or to tilt a fixture-rail 10a in a horizontal plane relative to its associated main rails 10, then each main-rail trolley 16 is provided with a friction locking brake 25 which is normally held in locking position, and which must be released before the main-rail trolley 16 can be thus moved along its main rail 10. If the main-rail trolleys 16 are shifted along their main rails 10 by a motor drive, these friction locking brakes 25 can be replaced, if desired, by retarding brakes 25a, which are non-locking; so that the main-rail trolley 16 can be shifted by normal manual or mechanical force, but is held frictionally against accidental movement and is stopped substantially immediately after the actuating force is released.

Each main-rail trolley 16 has a cam-shaft 26 which is adjacent and parallel to its shaft 23.

Cam-shaft 26 has cylindrical portions which are turnably supported in the respective vertical flanges 19. Each brake 25 comprises a horizontal plate 29 which has hooks 30 which are turnably supported, with no substantial friction, upon the shaft 23. If desired, as above noted, shaft 23 may be fixed to its flanges 19, so that shaft 23 is non-turnable, and roll 24 of shaft 23 may be turnably mounted on the non-turnable shaft 23.

The plate 29 is integral with a vertical plate 131, which is integral with a horizontal plate 132, to which a brake pad 133, of suitable frictional material, is fixed.

The entire assembly 29-31-32 is easily turnable around the axis of shaft 23, by means of said hooks 30.

One end of a compression spring 34 abuts the upper face of bottom flange 20. The other end of spring 34 abuts the bottom face of plate 32. The spring 34 normally exerts sufficient pressure to force brake-pad 33 against the bottom face of flange 15, to normally frictionally lock trolley 16 to its longitudinal rail 10. This normal locking position of brake 25 is shown in Fig. 4.

In addition to its cylindrical bearing portions in the flanges 19, and cam-shaft 26 has a recess 27, which has a planar wall 27a which is parallel to the axis of cam-shaft 26, and planar end-walls 27b which are perpendicular to said axis. One end of cam-shaft 26 also has an extension 28, of square cross-section, which extends laterally beyond the respective flange 19.

When cam-shaft 26 is in the normal locking position of Fig. 4, its planar wall 27a is horizontal, and plate 29 is located at least partially in recess 27, so that compres-

sion spring 34 then holds the brake-pad 33 in frictional locking position against the bottom face of bottom flange 15.

One end of a longitudinal release lever 35 is fixed to the extension 28 of cam-shaft 26. The other end of rod 35 has a notch 36. The hook 38 of a long rod 37 can be manually inserted into notch 36, in order manually to turn lever 35 and cam-shaft 26 to a release position in which the cylindrical part of cam-shaft 26 which is adjacent its recess 27, downwardly presses plate 29, thus downwardly moving brake-pad 33, and thus releasing the frictional lock. When the brake 25 is thus released, the rod 37 can be used to actuate trolley 16 manually along its main rail 10, in either direction.

Each fixture-rail trolley has a brake 25a.

Each trolley 17 has a shaft 26a, which is identical with cam-shaft 26. The brake 25a has a plate 32-31-33, with a friction pad 33 fixed to the bottom face of plate 32. Said plate 32 has upwardly directed hooks 30, which turnably abut and engage shaft 23.

The shaft 26a is always maintained in its position of Fig. 9, in which spring 34a keeps brake-pad 33 under selected braking pressure against flange 18.

This braking pressure of spring 34a is light, so that the fixture-rails 10a can be easily manually moved relative to their trolleys 17 to selected adjusted positions of said rails 10a. The relatively light springs 34a then hold the lateral rails against slipping or slight accidental pushing.

These brakes 25a, which may be designated as non-locking retarding brakes, may be used in trolleys 17, 17a and 52.

Each fixture-supporting trolley 17a supports one or more lighting fixtures or devices 47, which may be of the type shown in my application, Serial No. 377,885, filed September 1, 1953, and now abandoned.

Thus, a lazy-tongs device 45 may support a lamp housing 46a which has lamps 47. The upper end of each lazy-tongs device 45 is connected to the bottom plate of its trolley 17a by a swivel support 46.

An important feature of my invention is to support the long anterior current-conducting or main power cables 57, safely above the working level, in all positions of the fixture-supporting rails 10a. The inner end of each anterior cable 57 has an inner end-branch 57a, which is fixed to a junction box 56, which is fixed to a fixture-supporting rail 10a. If these long anterior cables 57 extend into the working level of the room, or become entangled with each other or with other objects, there is serious inconvenience and danger. As above noted, the length of a main power cable 57 may be many feet. The inlet of the main power cable into the room is sixteen feet above the floor, as one example. If not for the special suspension means provided herein, these long power cables would rest on the floor throughout most of their lengths.

As above noted, each cable-supporting rail 50 has a selected number, two or more, of associated cable-supporting trolleys 52. An external arm 55 is pivoted at 55a to each respective vertical plate 19 of each cable-supporting trolley 52. These arms 55 extend below the frames of the cable-supporting trolleys 52. A saddle 54 is pivoted to the lower ends of the two arms 55 of each cable-supporting trolley 52, below its frame. These saddles 54 have grooves which are parallel to rails 50 and 10. Each anterior cable 57 is slidably supported in the grooves of two or more saddles 54. Between its associated saddles 54, each anterior cable 57 has a plurality of bights. These bights are maintained parallel to rails 50 and 10 in this example. By providing a sufficient number of trolleys 52, these bights are maintained above the working level, and preferably above the main rails 10.

Thus, for convenient illustration, Fig. 5 shows two main rails 10 and three associated cable-supporting rails 50. These rails 50 can be located above said rails 10 at

a suitable height, and close to the median line between said two rails 10.

Each anterior cable 57 will then have an end-branch 57a, which will be close to the vertical position at all times, in all positions of the movable fixture-supporting rails 10a.

Each junction box 56 has a number of sockets or other connecting means, so that the lamps 47 of each fixture 46a can be connected to the source of electricity by respective intermediate or branch cables 59, which may be 10 laced through the respective lazy-tongs 45, to prevent dangling into the working level.

As above noted, the main-rail trolleys 16 or other trolleys may be actuated by motors, instead of manually shifting or tilting the fixture-supporting rails 10a relative to main rails 10.

For convenience of illustration, the motor drive is shown in Fig. 5 for only two associated main-rail trolleys 16, namely, for the left fixture-supporting rail 10a shown in Fig. 1.

Each of said two main-rail trolleys 16 has an electric motor (not illustrated) in a casing 70, which is external to an fixed to a respective vertical flange 19.

In the embodiment of Figs. 11 and 12, said motor has a motor-shaft 171, to which an actuating friction wheel 172 is fixed. Said wheel 172 has a frictional face or tire 173, which is pressed against the top face of the respective flange 15.

The electric motor is of the familiar reversible type, so that the main-rail trolley 16 can be driven in either direction along its main rail 10 by its motor. By thus actuating only one main-rail trolley 16, the associated fixture-supporting rail 10a can be tilted in a horizontal plane relative to main rails 10. Two such frictional actuating wheels 21—21a can be provided, one at each side of the respective vertical and planar flange 12 of the respective main rail 10.

In the embodiment of Figs. 13 and 14, a gear 180 is fixed to motor-shaft 71. This gear 180 meshes with gears 181, which are fixed to the rotatable shafts or pivot pins 22 of the wheels 21. In such case, the wheels 21 may have friction faces. If desired, as above noted, the pins 22 may be fixed to their respective flanges 19 and the wheels 21 may be turnable on their non-rotatable pins 22. In such case, the gears 181 are fixed to wheels 21. There may be two gears 180, at respective sides of the respective vertical flange 12, in which case, each set of wheels 21 at each side of flange 12 are thus connected to the motor-shaft 71.

If it is desired to operate the electric motors of each set or pair simultaneously and equally, the respective anterior or main power cable 57 is provided with a pair of motor-power wires for said motors, in addition to the wires for conducting electric current to the lamps 47 or other electrical devices in order to provide a motor circuit which is independent of the lighting circuit.

Each motor is connected to its junction box 56 by an intermediate or branch motor-cable 274. In order to prevent these branch motor-cables 274 from dangling into the working level, a clamp 275a is fixed to the respective branch 275a of the respective anterior cable 57. There are two extended tension springs 275. One end of each tension spring 275 is fixed to clamp 275a. The other end of each extended tension spring 275 has a hook 275b, through which the respective intermediate motor-cable 274 extends slidably. When a fixture-supporting rail 10 is slid laterally relative to its fixture-rail trolleys 17, the respective junction box 56 approaches one of the motor-casings 270. However, the springs 275 are under sufficient tension and extension so that the respective spring 275 will then contract sufficiently to hold the respective intermediate motor-cable 274 from dangling below the respective fixture-rail 10a.

If it is desired to control each motor individually, the

respective anterior cable 57 has two wires or a respective motor circuit for each motor, and each motor circuit has its own control switch at the remote-control station for starting, stopping and reversing each motor individually. In such case, each motor is independently supplied with current through its respective intermediate or branch motor-cable 274, so that each motor circuit is independent of the other motor circuit, and all the motor circuits are independent of all the lighting circuits.

All the main wires and cables 57 and 274 of the system can be thus maintained above the fixture-supporting rails 10a, with the exception of the intermediate or branch wires 59, which are maintained above the housings 46a. Even if the main wires or cables dangle below the fixture-supporting rails 10a, they can be kept at a safe level, such as six feet or eight feet above the level of the floor. By having the branch wires 59 through the supports 45, said branch wires are maintained upwardly from the housings 46a, to provide the necessary safety factor and to keep the working level unobstructed.

Numerous changes can be made in this embodiment, without departing from the scope of the invention. Thus, the main rail 10 may be replaced by inverted T-rails. The annular rims 21a of the wheels 21 provide means for preventing any substantial horizontal twisting or sideways movement between a trolley and its rail. Other means could be substituted for this purpose. The invention is not limited to horizontal main rails 10, or to rails which have planar supporting surfaces, or to the specific shape of the I-rails illustrated herein.

The system can be used as an electrical supply system for any electrical devices.

Also, for some purposes, the supporting rails 10 and 10a are not necessarily overhead rails.

The trolleys are merely one means for providing easy movement relative to a rail, and equivalent means are included, whenever a trolley is mentioned in any claim. Thus, the trolleys may be replaced by slides. Also, the invention is not limited to parallel main rails 10 or to fixed main rails 10.

This application is a continuation-in-part of my applications Serial No. 377,885, filed Sept. 1, 1953, and Serial No. 480,243, filed January 6, 1955, both said applications being now abandoned.

What is claimed is:

1. In a studio lighting system, a fixed overhead horizontal supporting means, roller elements perpendicularly disposed on said supporting means for movement to and fro thereon, bracket means depending from the roller elements and rotatable about an axis perpendicular to the axis of the supporting means, roller members rotatably carried by the bracket means and arranged perpendicular to the supporting means, a beam element slidably carried by the roller members and horizontally supported thereby for axial movement, stop means at the ends of said beam element engageable with the roller members to limit the axial movement of the beam element thereon, a depending supporting element slidably mounted at its upper end on the beam element and movable from one end to the other end of the beam element, a light device carried by the lower end of the supporting element and having an electrical conductor cord attached thereto and terminating in an electrical connector and a plurality of longitudinally spaced electrical convenience outlets mounted on the supporting means and adapted to receive the electrical connector.

2. An electrical supply lighting system which comprises substantially horizontal main-rails which are longitudinally disposed and which are separated laterally from each other, main trolleys supported by and depending from said main-rails, auxiliary trolleys connected to and depending from said main-trolleys, said respective auxiliary trolleys being connected to respective main-trolleys by respective vertical pivots, auxiliary horizontal rails supported by and depending below said auxil-

iary trolleys, said auxiliary rails being laterally disposed and being laterally movable on the respective auxiliary trolleys; longitudinally-disposed cable-supporting rails located above said main-rails; there being one cable-supporting rail associated with each said auxiliary rail, fixture-supporting trolleys mounted on said auxiliary rails and supporting lighting-fixtures; respective junction boxes fixed to said auxiliary rails, a flexible power cable associated with each junction box; each power cable having an inlet end which is adapted to be connected to a source of electric power and an outlet leg which has an outlet end which is connected to a respective junction box; cable-trolleys movably supported on said cable rails; each said cable being supported by respective cable-trolleys above said main-rails up to said outlet leg, said outlet leg depending from the respective cable-trolley to the respective junction box, and a wire connecting the respective junction box to the respective lighting fixture.

3. A system according to claim 2, in which each outlet leg is between a pair of main-trolleys, each outlet leg

being connected above its respective junction box to the respective main trolleys by lateral connections which include a tension spring at each side of said outlet leg.
